UNITED STATES PATENT OFFICE.

BERTHA MEYER, OF KANSAS CITY, MISSOURI.

DESIGN FOR A SPOON.

SPECIFICATION forming part of Design No. 21,739, dated August 2, 1892.

Application filed June 22, 1892. Serial No. 437,657. Term of patent 3½ years.

To all whom it may concern:

Be it known that I, BERTHA MEYER, a citizen of the United States, residing at Kansas City, in the county of Jackson and State of Missouri, have invented and produced a new and original Design for Spoons; and I do declare the following to be a full, clear, and exact description of the invention, such as will enable others skilled in the art to which it applies to make and use the same, reference being had to the accompanying drawing, which forms a part of this specification.

My invention relates to a new and original design for a spoon, of which the following is a specification, reference being had to the accompanying drawing, which forms a part thereof.

The figure is a front view of the handle and bowl of a spoon, showing my design, the leading features of which are "Grandpa's Hat" resting on a scroll or bracket forming the end of the handle, the scroll or bracket inclosing

a log cabin with a door in front, coon-skin nailed to the front wall on the left of the door, small window in end of cabin, ends of the scroll resting on the outspread wings of an eagle, eagle resting on shield, right foot of eagle holding arrows, and shield showing perpendicular stripes or bars. The lower point of shield rests on the end of an inverted cornucopia, partially inclosing the American flag, showing thirteen or more stars and the stripes, the flag-staff and flag constituting the small part of the handle.

What I claim is—

The design for a spoon, substantially as set forth.

In testimony whereof I have affixed my signature in presence of two witnesses.

BERTHA MEYER.
